(57) **CLAIM**

The ornamental design for an earphone, as shown and described.

DESCRIPTION

FIG. 1 is a top, front, and right perspective view of a first embodiment of the earphone showing our new design.

FIG. 2 is a bottom, rear, and left perspective view of the earphone of FIG. 1.

FIG. 3 is a front view of the earphone of FIG. 1.

FIG. 4 is a rear view of the earphone of FIG. 1.

FIG. 5 is a left side view of the earphone of FIG. 1.

FIG. 6 is a right side view of the earphone of FIG. 1.

FIG. 7 is a top view of the earphone of FIG. 1.

FIG. 8 is a bottom view of the earphone of FIG. 1.

FIG. 9 is a top, front, and right perspective view of a second embodiment of the earphone.

FIG. 10 is a bottom, rear, and left perspective view of the earphone of FIG. 9.

FIG. 11 is a front view of the earphone of FIG. 9.

FIG. 12 is a rear view of the earphone of FIG. 9.

FIG. 13 is a left side view of the earphone of FIG. 9.

FIG. 14 is a right side view of the earphone of FIG. 9.

FIG. 15 is a top view of the earphone of FIG. 9; and,

FIG. 16 is a bottom view of the earphone of FIG. 9.

The design includes ornamental features of an earphone as shown and described. The earphone can be attached to an ear hook.

The ornamental design which is claimed is shown in solid lines in the drawings. The broken line showing in FIGS. 1-16 illustrates the environment, which forms no part of the
